UNITED STATES PATENT OFFICE.

ARTHUR BALDWIN AND JOHN CLEMENT, OF PRAIRIE DU SAC, WISCONSIN.

FENCE-WIRE-WINDING MACHINE.

SPECIFICATION forming part of Letters Patent No. 398,215, dated February 19, 1889.

Application filed November 7, 1888. Serial No. 290,214. (No model.)

To all whom it may concern:

Be it known that we, ARTHUR BALDWIN and JOHN CLEMENT, citizens of the United States, residing at Prairie du Sac, in the county 5 of Sauk and State of Wisconsin, have invented new and useful Improvements in Fence-Wire-Winding Machines, of which the following is a specification.

Our invention relates to improvements in 10 machines for winding barbed fence-wire; and it consists in certain novel features hereinafter described and claimed.

In the accompanying drawings, Figure 1 is 15 a perspective view showing the device in the operative position. Fig. 2 is a side view showing the device tilted upward into position to permit the removal of the wound wire. Fig. 3 is a longitudinal section with the parts in the position shown in Fig. 1. Fig. 4 is a detail 20 view showing the ratchet, pawl, and crank arm.

Referring to the drawings by letter, A designates a carriage consisting of the arched axle B and the supporting-wheels C, as shown. To the vertical portions of the arched axle we 25 secure the front ends of the push-bars D, the rear ends of which are connected by a cross-bar, E, serving as a handle to propel and steer the machine. At an intermediate point of the push-bars we secure between the same the 30 cross-bar F, and from the ends of said cross-bar we pivotally mount the supporting-legs G G, the lower ends of which are adapted to rest on the ground and support the push-bars in a horizontal position. The said cross-bar and 35 the push-bars are suitably braced by the inclined bars or braces I I, extending from the cross-bar to the yoke of the axle.

J J designate the reel-arms, which are 40 loosely mounted at their upper ends on the yoke of the axle and have hooks K K at their lower ends, which serve as bearings for the reel-shaft L, as shown. The said reel-shaft is provided on one end with a gear-wheel, M, which meshes with the pinion N on the front 45 end of the driving-shaft O. The said driving-shaft O is mounted in bearings on the side of one of the push-bars, as shown. The driving-shaft is further provided with a crank arm or handle, P, at its rear end, and has mounted 50 thereon a ratchet-wheel, Q, which is engaged by a pawl, R, secured to the handle E to prevent backward rotation of the said shaft.

The reel-shaft is provided between the reel-arms J J with a stationary plate, S, having hooked ends adapted to engage and secure the 55 end of the wire-carrying spool, so that when the said shaft is rotated the wire will be wound thereon.

T designates a collar, which is screwed on the reel-shaft by a set-screw, U, as shown. 60 This collar, it will be seen, can be readily removed when it is desired to remove the spool from the shaft, and it is also adjustable along the said shaft, so as to accommodate spools of different lengths. 65

u u designate spring-pawls, which are secured at their rear ends to the inner sides of the push-bars, and have their front ends engaging the reel-arms J J to prevent the same swinging forward when the wire is being 70 wound, and thereby releasing the tension.

V V designate guides having their front ends secured to forwardly-extending arms W W, projecting from the yoke of the axle, and having their rear ends secured to brackets X X, projecting inwardly from the front ends of the shafts. The reel-arms play in these guides when the reel is being swung forward to remove the wire after being wound or to secure the end of the same preparatory to winding. 80

In practice, when it is desired to apply the wire to a fence, one end of the wire is secured 85 permanently to a post. The pawl R is then disengaged from the ratchet-wheel Q, after which the machine is drawn along the line of the proposed fence, when the tension of the wire will cause the reel to rotate, so as to allow the wire to unwind therefrom. When it is desired to wind the wire, the free end of the wire is secured to the spool, and the driving-shaft is then 90 rotated, so as to impart motion to the gear-wheel, and consequently to the reel-shaft. The wire will thus be wound upon the spool, when the tension of the wire will draw the machine along the line of the fence, so that 95 the operator only has to steer the machine and is not obliged to push the same, one hand being free to rotate the driving-shaft and thereby wind the wire. When it is desired to remove the wire, the machine is tilted, as shown 100 at F, so that the reel-arms J J will swing forward through the guides u u and lower the reel to the ground. The hooks at the lower end of the reel-arms are then disengaged from

the reel-shaft and the shaft removed from the spool. A full spool can then be applied by inserting the shaft through the spool and securing it, after which the reel-arms are engaged with the reel-shaft and the machine turned to a horizontal position, thereby lifting the reel. In this way the labor of raising the heavy spool is reduced to a minimum.

It will thus be seen that we have provided 10 a very simple and efficient machine which is composed of few parts, and can consequently be manufactured and sold at a small cost, and is not liable to get out of order.

Having thus described our invention, what 15 we claim, and desire to secure by Letters Patent, is—

1. In a machine for winding fence-wire, the combination of the axle, the swinging reel-arms having their upper ends hung thereon, 20 the reel-shaft supported by said arms, and mechanism for rotating the reel-shaft, as set forth.

2. The combination of the axle, the push-bars secured thereto, the reel-arms hung on 25 the axle, the pawls secured to the push-bars and engaging the reel-arms, the reel-shaft supported by said arms, and mechanism for rotating said shaft, as set forth.

3. The combination of the axle, the push-bars secured thereto, the reel-arms hung on 30 the axle, the guides for said arms supported by the push-bars and the axle, the pawls secured to the push-bars and engaging said arms, the reel-shaft supported by said arms, and mechanism for rotating said shaft, as set forth. 35

4. The improved machine for winding fence-wire, comprising the axle, the push-bars secured thereto, the reel-arms hung on the axle, the pawls secured to the push-bars and engaging said arms, guides for said arms supported by the axle and the push-bars, the reel-shaft supported by said arms, the driving-shaft mounted on one of the push-bars and geared to the reel-shaft, the cross-bar connecting the push-bars, and the supporting- 40 legs pivoted to said cross-bar, as specified. 45

In testimony that we claim the foregoing as our own we have hereto affixed our signatures in presence of two witnesses.

ARTHUR BALDWIN.
JOHN CLEMENT.
